ATTORNEY

UNITED STATES PATENT OFFICE.

HAROLD S. LABOMBARDE, OF NASHUA, NEW HAMPSHIRE.

BUNDLE TIER.

Application filed July 23, 1923. Serial No. 653,154.

To all whom it may concern:

Be it known that I, HAROLD S. LABOMBARDE, a citizen of the United States, and resident of Nashua, in the county of Hillsboro and State of New Hampshire, have invented certain new and useful Improvements in Bundle Tiers, of which the following is a specification.

This invention relates to mechanism for securing together, in the form of bundles, the product of other machines such as box making or envelope machines, in order to produce packages ready for shipment.

Most machines which convert blanks into flat folded boxes deliver the folded boxes in overlapping condition upon a slowly travelling belt, the latter constituting a travelling platform from which an attendant gathers the boxes in bunches preliminary to preparing them for shipment or storage. Usually certain devices called counters are employed to effect a slight lateral displacement of each 25th or 50th flat box in the row on the belt or platform, to facilitate the picking up, by the attendant, of bunches which are uniform as to the numbers of the boxes in such bunches. It has been the custom for the attendant who picks up the bunches or groups to place them on racks which are movable to some convenient location in proximity to a tying or knotting machine, or where they can be tied by hand, to prepare the articles for the employee who puts the packages in shipping boxes. All of this requires several employees to attend to the output of one folding machine of the high-speed character now generally employed.

One of the objects of the present invention is to provide a machine having a tier and including a conveyor for carrying groups of flat articles to position to be operated upon by the tier, and means for reducing the size of each group when it reaches position to be tied, whereby each group is so tied while under compression that no relative slippage of the members of a group is likely to occur during subsequent handling.

Another object is to provide a machine of the character referred to wherein a single source of power operates both the tier and the conveyor which advances the groups to position to be tied, whereby any change of speed of movement of the conveyor will not

affect the timing of the operation of the tier.

Another object is to provide a machine having the travelling platform from which the attendant gathers the bunches or groups so located relatively to the tier that said attendant, while remaining in one position close to one side of the platform, can transfer the bunches to the tier carrier without having to move from that position.

With the above objects in view, and other objects as hereinafter explained, the invention consists in the construction and combinations of parts substantially as herein-after described and claimed.

Of the accompanying drawing:—

Figure 1 is a plan view of the machine, including the travelling platform which receives flat folded boxes in a row of overlapped boxes and from which an attendant gathers the boxes in bunches and transfers them to the carrier of the tier.

Figure 2 is a side elevation of the same.

Figure 3 is a detail side elevation of a portion of the machine, on a larger scale than in Figure 2, and showing the pressure mechanism in both full and dotted lines, to illustrate idle and operative positions thereof.

Figure 4 is a detail view illustrating the devices which actuate the tripper of the tier.

Figure 5 is a detail sectional view of the grooved rails which support the carrier chains.

Figure 6 is a detail side elevation to illustrate the action of the tripping devices.

Figure 7 is a view similar to Figure 3 but omitting some of the details of said Figure 3.

Similar reference characters designate similar parts in all of the views.

The frame of the machine includes side bars 12 supported by legs 13, a portion of one of the side bars being inset, as at 12', for a reason explained hereinafter.

A belt 14 which constitutes the travelling platform referred to, is mounted on drums 15 carried by shafts 16 the bearings for which, unnecessary to illustrate, are supported by the side bars 12. Said belt, as is customary with the receiving belts onto which flat folded boxes are delivered in an overlapping row by machines which fold the

blanks, is usually driven at a quite slow speed. It serves as a table from which an attendant takes the boxes in bunches. Such a row of boxes is indicated at *a* in Figure 1. 5 At certain intervals boxes are laterally displaced as indicated at *a'*, this being effected by what is known as a counter in the art. The belt 14 is necessarily quite wide in order to accommodate the largest size of boxes 10 which well known folding machines produce.

The mechanism which ties the bunches or bundles of boxes is mounted close to the edge of the belt opposite the inset bar section 12'. Said inset portion enables the attendant to stand quite close to the belt so as to reach across it, after picking up a bunch, and place that bunch on the tier carrier without having to make any turn 15 of the body or arms while doing so, thereby effecting a material saving in time. The frame of the machine must be somewhat wider than a person could readily reach across, in order to provide bearings for the 20 belt drum shafts. Therefore the inset portion 12' is provided between the drums and opposite the tier mechanism which will now be described.

Chains 17 are mounted on sprockets 18 30 carried by shafts 19, 20. The shaft 20 extends out from the frame, through a tubular bracket 21 (Fig. 1) having a housing 22 at its end. Said shaft 20 has, within the housing, a gear 23 (Fig. 2) driven by a 35 worm 24 carried by a shaft 25, the latter having a pulley 26 driven by a belt 27 from the pulley 28 of the shaft 29 of a motor 30 supported by a casting or bracket 31.

The shaft 29 of the motor has another 40 pulley 32 which, through belt 33, actuates the tier mechanism one member of which is indicated at 34 (Fig. 2). As the tier used and but conventionally illustrated may be of any well known or preferred type, and 45 as the specific structure thereof forms no part of the present invention, illustration and description of its details are unnecessary. Such tiers customarily operate but once for each release of a clutch drive 50 connection, such release being effected by a trip member. A feature of the present invention however resides in the fact that a single source of power, as the motor 30, operates both the tier and the bundle-convey 55 veyor chains 17 through the two belts 27, 33, just described. The reason for this is to avoid liability of any change of speed of travel of the conveyor chains 17 affecting the timing of operation of the tier.

60 Each chain has secured to it, at spaced intervals, a series of upright members which, for convenience of description, are herein referred to as jaws 35. The jaws of the two chains are side by side and the front walls 65 of one pair coact with the rear walls of the

next pair in forming a pocket for receiving between said walls a bunch of flat articles as indicated at *a* in Figure 2. The upper portions of the rear walls are preferably bevelled or inclined somewhat as indicated, so 70 that the spaces or pockets for the bunches will be bell-mouthed to facilitate the placing of the bunches therein. This provision also facilitates the tilting of the tied bundles onto the inclined table shown at the right in 75 Figure 2, at the conclusion of the operation as hereinafter described.

Each jaw member has a rearwardly extending arm 36, the arms of each two members of a pair serving as a floor to support the flat articles edgewise and prevent contact with the chains 17 which are underneath said arms. A lever 37, (Figs. 2, 4 and 6) is pivoted at 38 to one of the jaws of each pair and is provided with a weight 39 to normally hold the lever in the position shown by full lines in Figure 4, a stop pin 40 being provided to limit the oscillations permitted as indicated by the full and dotted line positions of said figure. The tip 80 end of the lever is bent down at 41 to provide what is hereinafter referred to as a hook to engage a member to start the tier as will be explained.

The upper stretches of the chains 17 travel 95 in longitudinally grooved rails 42, the walls of said grooves (Fig. 5) having shoulders or ribs 43 so that the links of the chains, which run below said ribs, can not tilt endwise while in the grooves. The jaws 35 are secured to blocks 44 which, in turn, are secured to properly spaced chain links.

An upright plate 45 is suitably supported by the frame of the machine between one edge of the belt 14 (Fig. 1) and the conveyor chains 17, said plate being below the plane of the upper stretches of said chains (Fig. 2). The attendant who picks up bunches of articles from the belt 14 joggles each bunch against the plate 45 to bring the edges of all of the articles in the bunch into alignment, and then when depositing the bunch in the space between the jaws as shown by comparing Figures 1 and 2, the end of the bunch farthest from her is placed against a plate 46 which serves as a stop to determine the proper position for the bunch so that the string to be later tied around the bunch will be at its mid-length. Since the machine is to be used for bundling different sizes of articles such as paper boxes, the stop or guide plate 46 is adjustably mounted on a pair of outwardly extending supports 46'.

125 Each bunch of articles is conveyed along by the jaws to position to be tied, and just before the tying operation is performed the bunch is compressed and held so until the tying operation is completed. The mechanism for doing this will now be described.

Referring to Figures 1, 2, 3 and 7, especially the latter two, a rock shaft 47 is mounted in the frame of the machine and has a pinion 48 engaged and operated by a vertically movable rack 49, said rack being reciprocated by the mechanism of the tier through a connecting link 50. As the tier mechanism is of a well known type, it is sufficient for present purposes to state that when the clutch of the tier driving mechanism is released, a moving part of the regular tier acts through the link 50 to quickly lower the rack just before the tier member 34 swings to carry string 6 around the bunch which has been brought to position.

Pivottally mounted on the rock shaft 47 is an arm 51 having bearings in which two rods 52 are mounted to slide, said two rods carrying a pressure plate 53. Springs 54 coiled around the rods are confined between the slide bearings for said rods and the heads 55 of the rods. Tightly secured to the rock shaft adjacent to the loosely mounted arm 51 is a short arm 56 from which a rigid rod 57 extends, said rod being connected by a link 58 with the back of the pressure plate. The arm 51 has a short end 59 extending downwardly, and a fixed stop 60 is located to coact with said short end 59 in limiting actuation of the arm 51 to the position shown by full lines in Figure 7 and dotted lines in Figure 3. In Figure 2 the parts just described are shown in their upper position because they would not show clearly if lowered. As a matter of fact, said parts are only in that position when operating to exert pressure on a bunch. When the rack 49 descends and rocks the shaft 47, the swinging up of the rod 57 acts through link 58 to swing the parts described up from the position shown by full lines in Figure 7, carrying the plate 53 up between the two jaws of a pair so that said plate contacts with the front article of the bunch which is being advanced by the jaws. The arm 51 can not swing any further, owing to the stop 60, but a little further rotation of the rock shaft causes the plate 53 to move farther toward the dotted line position indicated in Figure 7 to compress the bunch. At the same time the jaws which are behind the bunch are advancing and this also causes compression since the plate 53 is arresting the front portion of the bunch. It may be stated here that the rack 49 moves down and then up again very quickly so that the pressure plate swings back to the full line position indicated in Figure 3 as soon as the tying operation, which itself is very quickly performed, is completed.

A stop screw 61 in a bracket 62 below the lower end of the rack 49 serves to limit the downward movement of the rack so that the amount of compressive thrust which can be given to the plate 53 after the arm 51 has

reached its vertical position, can be variably determined to suit the character of the articles being operated upon and the amount of compression which it is best to impart thereto.

In case it should be desirable to temporarily arrest movement of the conveyor chains 17 during the operation of tying, I may employ a lever 63 pivoted at 64 and having a hook-shaped outer end having a heel 65 in position so that when the arm 51 swings up (see Fig. 7) its short end 59 will contact with said heel and elevate the hook end of the lever (as indicated by dotted lines in Figure 3) into the path of movement of a roller pin 66 projecting from the side of one of the sprockets 18 carried by the driven shaft 20. Since the shaft 20 is not so positively driven that its rotation can not be stopped, the hook lever is able to attain this result. If there is any tendency of the hook lever to stick in its upper position, the descent of the arm 51 upon it will lower it so as to release the pin 66.

The operation of the string-carrying and knotting mechanism of the tier, and the practically simultaneous operation of the bunch presser, are controlled by the presence of the bunches between the jaws, but without requiring the articles themselves to contact with anything to effect such operation. When a bunch is deposited between the jaws its weight depresses the lever 37 from the normal position shown by Figure 4 and portions of Figure 2, to the position shown by Figure 6, the resistance to such movement afforded by the weight 39 being very slight. The lower edges of the articles in the bunch come to rest on the arms 36 of the jaws and do not contact with the chains and are therefore not liable to be injured in any way, as by notching or tearing. The depression of the lever 37 carries its hook end 41 down to position where it will, as the conveyor chains continue to travel in the direction of the arrow (Fig. 6), cause the tier to operate by releasing the clutch thereof as presently described. If there is no bunch in the pocket or space between the jaws, there will be no operation of the tier because the lever 37 will remain elevated.

A weight 67 (Fig. 6) mounted on a pivot 68 has its upper end formed as a lug 69 in the path of movement of the hook end 41 of the lever 37 when the latter is depressed. 70 indicates the shaft of the release clutch of the tier. Said shaft has an arm 71 secured to it, and a screw 72 carried by said arm has its tip in position to be struck by the lower end of the weight 67 when the latter swings back after being tilted by the hook 41 acting on its lug 69. When the weight swings back into contact

with the screw 72 it strikes with sufficient force to rock the shaft 70 and effect release of the clutch of the tier mechanism, and the member 34 of the latter swings around and cooperates with the other members of the tier mechanism to carry the string around the bunch which is under compression and knot the string in the usual manner of the tier.

10 When the hook 63 is employed and the conveyor is stopped during tying, the hook 41 occupies the position indicated by dotted lines in Figure 4 and will have passed the lug 69 of the weighted lever 67 (Fig. 6) so that the latter will have swung back and effected release of the tying mechanism as just described.

At the delivery end of the bundle conveyor is a table 73, preferably inclined as indicated in Figure 2. It is slotted as at 74 (Fig. 1) to permit the jaws to pass down through said slots when the jaws follow the movement of the chains around the sprockets 18 of the driven shaft 20. When 25 the jaws begin this circular movement, their arms 36 necessarily rise and lift the tied bundle as shown at the right in Figure 2 above and onto the table 73, the jaws and their arms 36 then continuing their movement down through the slots of the table, leaving the bundle free to be either picked up from the table or to slide off therefrom into any suitable receptacle.

To enable an attendant to gather bunches 35 of the articles *a* from the slowly travelling platform 14 without undue lateral displacement of some of the articles, I provide a gravity roll (or a spring depressed roll) 75 in position to bear on the row of articles 40 as the latter approach position to be gathered. I do not confine myself to the location of said roll in the position indicated in Figures 1 and 2. It may be nearer the outer end of the row than illustrated. In any 45 case, the roll is near enough to the place where the attendant stands to enable it to apply resistance to displacement of the articles when the attendant gathers a bunch by a movement of the hand or hands in a direction opposite to that in which the row 50 of articles is moving.

As the operations of the different parts of the machine have been explained in connection with the descriptions of the details 55 thereof, further reference to the operation of the machine as a whole is unnecessary.

Having now described my invention, I claim:

1. A machine of the character described 60 comprising a tier, means for automatically moving a group of flat articles while under slight compression to position to be operated upon by the tier, means for automatically applying pressure to said group during the 65 tying operation, without interfering with

further movement of the articles in the same direction, and tripping mechanism for the tier in position to be caused to act by a group approaching position to be tied.

2. A machine of the character described 70 comprising a frame having an inset portion, a travelling platform in close proximity to said inset portion, and a bunch conveyor and tier in close proximity to the opposite side of the said platform. 75

3. In a machine of the character described, a conveyor provided with means for supporting groups of articles, a tier for operating successively on groups presented to it by the conveyor, a motor having a shaft provided with two pulleys, a belt mounted on each pulley, connections for driving the conveyor by means of one of said belts, and connections for operating the tier by means of the other of said belts. 80

4. The combination with mechanism for confining groups of flat articles, of a conveyor comprising chains having jaw members provided with front and rear walls with rearwardly extending arms. 85

5. The combination with mechanism for confining groups of flat articles, of a conveyor comprising chains having jaw members provided with front and rear walls, said walls being formed to provide bell-mouthed spaces between them. 95

6. The combination with mechanism for confining groups of flat articles, of a conveyor comprising chains having jaw members provided with arms extending rearwardly over the chains, and means connected with each jaw member to control the operation of the confining mechanism. 100

7. A machine of the character described comprising a tier, chains having spaced jaws 105 for carrying groups of flat articles to position to be operated upon by the tier, and tripping devices connected with the chains for controlling the operation of the tier.

8. A machine of the character described 110 comprising a tier, an endless conveyor having bunch holders, a lever pivoted to each holder and having a hook, and means adapted to be engaged by said hook to effect operation of the tier. 115

9. A machine of the character described comprising a tier, an endless conveyor having bunch holders, a hook lever pivoted to each holder and weighted to cause the lever to normally occupy a position to be shifted by the presence of a bunch in the holder, and means adapted to be engaged by the hook of the lever when shifted to effect operation of the tier. 120

10. A machine of the character described 125 comprising a tier, chains having spaced jaws for carrying groups of articles to position to be operated upon by the tier, grooved rails for supporting the upper stretches of the chains, and means for preventing end- 130

wise tilting of the jaws while travelling along the grooves of the rails.

11. A machine of the character described comprising a tier, grooved rails and chains movable therealong, the grooves of the rails having ribs projecting inwardly above the links of the chains, and bunch holding jaws secured to the chains.

12. A machine of the character described comprising a tier, a conveyor for carrying groups of flat articles to position to be operated upon by the tier, a row-supporting belt extending along one side of the conveyor, and an upright plate between the belt and conveyor to provide a surface against which an attendant may aline the articles in a group taken from the belt.

13. In a machine having a tier and an endless series of holders for conveying groups of articles to be tied, a rock shaft having a pinion, a reciprocatory rack engaging said pinion, an arm pivotally mounted on said shaft, a pair of rods slidably mounted in said arm and carrying a pressure plate, and a second arm secured to the rock shaft and having connections with said pressure plate to move the latter toward the front of each group in a holder approaching the tier.

14. In a machine having a tier and an endless series of holders for conveying groups of articles to be tied, a movable pressure plate, means for moving said plate toward the front of each group in a holder approaching the tier, and means for adjusting

the amount of pressure imparted by said plate.

15. In a machine having a tier and an endless series of holders for conveying groups of articles to be tied, a rock shaft having a pinion, a reciprocatory rack engaging said pinion, an arm pivotally mounted on said shaft, a pair of rods slidably mounted in said arm and carrying a pressure plate, a second arm secured to the rock shaft and having connections with said pressure plate to move the latter toward the front of each group in a holder approaching the tier, and an adjustable stop opposite an end of the rack to limit the pressure-imparting movement of the rock shaft and the parts carried thereby.

16. The combination with a machine having a tier and a conveyor comprising an endless series of bunch holders having rearwardly extending arms, for supporting the bunches, of a table for receiving tied bunches, said table being slotted to permit said arms to pass upwardly and tilt the tied bunches onto said table.

17. The combination with a travelling platform for a row of overlying flat articles, of means adjacent said platform for tying up bunches of articles transferred thereto from the platform, and means for resisting displacement of articles to be left in the row when a bunch is gathered therefrom.

In testimony whereof I have affixed my signature.

HAROLD S. LABOMBARDE.
